UNITED STATES PATENT OFFICE.

JAMES M. BROWN, OF PITTSBURGH, PENNSYLVANIA, ASSIGNOR TO WESTINGHOUSE ELECTRIC & MANUFACTURING COMPANY, A CORPORATION OF PENNSYLVANIA.

BUS-BAR SUPPORT.

Application filed November 28, 1919. Serial No. 340,980.

To all whom it may concern:

Be it known that I, JAMES M. BROWN, a citizen of the United States, and a resident of Pittsburgh, in the county of Allegheny and State of Pennsylvania, have invented a new and useful Improvement in Bus-Bar Supports, of which the following is a specification.

My invention relates to electrical conductor-supporting devices and particularly to devices for supporting bus-bars.

One object of my invention is to provide a device for supporting bus-bars that shall be effectively secured opposite an opening 15 in a bus-bar wall or panel structure in such manner as to permit withdrawal from its position through the opening.

Another object of my invention is to provide adjustable supporting means to permit 20 a bus-bar or other conductor to be adjusted toward and away from a panel or wall on which it is supported.

Another object of my invention is to provide anchor or securing members that shall 25 be so united to a bus-bar insulator by a body of molded material as to adapt the insulator to be securely fastened to a supporting member and to permit a member for attachment to the insulator to be securely 30 fastened thereto.

In practicing my invention, I provide an insulator of the pillar type having peripheral notches or other means by which a body of molded material may be caused 35 to effectively adhere thereto. Screw-threaded nuts or other securing members are embedded in the molded material for the reception, at one end of the insulator, of bus-bar-attaching members and, at the other 40 end of the insulator, of a screw-threaded base plate.

The base plate co-operates with a supporting member disposed on, and surrounding 45 an opening in, a bus-bar structure wall or panel and permits the insulator and certain of its co-operating members to be dismounted from operative position by withdrawal through the opening in the wall.

Figure 1, of the accompanying drawings, 50 is a side view, partially in elevation and partially in section, of a bus-bar structure embodying my invention, and Fig. 2 is a fragmentary detail view, similar to a portion of Fig. 1, showing a modified form of 55 structure embodying my invention.

In general, my device comprises an insulator 1, preferably of porcelain, shell or cap members 2 and 3 secured to the ends of the member 1 by bodies of molded material 4, such as cement or bearing metal, bus-bar securing members 5 for supporting bus-bars 6, a base plate 7 and a supporting member 8 secured adjacent to an opening 9 in a panel 10, or other structure, by bolts 11.

Each end of the insulator 1 is provided 60 with peripheral notches or recesses 12 that serve as anchoring means for an annular body of the molded material 4 that is enclosed by the cap members 2 and 3. The latter are provided with openings 13 65 through which screws or other members 15 extend. Nuts 14 or other securing members are embedded in the material 4 for the reception of the members 15. The members 15 constitute means by which the members 5 may be secured to the outer end of the insulator and means by which the base plate 7 may be secured to the base of the insulator.

The supporting member 8 has a central 80 opening which registers with the opening 9 in the wall 10 and is interiorly screw threaded for the reception of a sleeve 16 that is both interiorly and exteriorly screw threaded. The base plate 7 is threaded to 85 be received by the sleeve 16, as is, also, an exteriorly-threaded sleeve 17 having peripheral notches 18 for co-operation with a spanner wrench or other device which may be employed to turn the sleeve 17 into locking 90 engagement with the base plate 7. An annular lock nut or ring 19 engages the outer threads of the sleeve 16 and may be moved into engagement with the supporting member 8.

In manufacture, the nuts 14 are provided 95 with temporary bolts and are placed in co-operative position with respect to the shell or cap members 2 and 3 and the caps placed over the ends of the insulator 1, after which, the material 4 is poured, while in a plastic state, through spaces 20, between the insulator 1 and the inner edges of the cap member 2 and 3, to fill the caps and the notches 12. When the material 4 has set, the temporary bolts may be withdrawn, leaving the nuts 14 securely embedded in the material 4 and ready for the reception of the bolts 15.

By loosening the members 17 and 19 by 110

- a turning movement, the sleeve 16 may be released and subsequently moved with respect to the plate 8 for adjusting the insulator longitudinally to better place it with respect to the bus bars 6 or the wall 10 and to be locked in adjusted position, or the insulator may be withdrawn through the opening 9 after the bus bars 6 have been detached from the structure.
- 10 In Fig. 2, the modified form of device is substantially the same as the device described above, with the exception that the intermediate sleeve 16 is omitted. In this form, the base member 7 directly engages the supporting member 8, and a lock nut or ring 21 serves to lock the parts in adjusted position.
- The device of Fig. 2 is simpler in construction than the device of Fig. 1, but requires 20 the turning of the insulator to adjust or withdraw it, which is not true of the device shown in Fig. 1.
- While I have shown and described particular forms of my invention, changes may 25 be effected therein without departing from the spirit and scope thereof, as set forth in the appended claims.
- I claim as my invention:
1. A bus-bar structure comprising an insulator, an annular exteriorly-threaded base member for the insulator and a supporting member for the base member having an interiorly-threaded aperture through which the insulator may be withdrawn.
  2. A bus-bar structure comprising an insulator, a base member therefor and a supporting member for the base member having an aperture through which the insulator may be withdrawn.
  3. A bus-bar-supporting device aligned with an opening in a bus-bar wall or panel structure, and means for securing the supporting device to the wall or panel and for permitting its withdrawal through the opening.
  4. The combination with a panel having an aperture therein, of an insulator that may pass through the opening, and a support therefor for securing the insulator to the panel and permitting withdrawal of the insulator through the said opening.
  5. A bus-bar structure comprising an insulator, a support for supporting the insulator in a determined position on one side of the support and having an opening through which the insulator may be moved to the opposite side of the support.
  6. A bus-bar structure comprising a base member having a threaded aperture therein, an externally and internally threaded sleeve disposed in adjustable engagement with the base member and an insulator that may pass through the aperture in the base member having a threaded portion engaging the internal threads of the said sleeve.

7. A bus-bar structure comprising a base member having a threaded aperture therein, a sleeve threaded externally and internally disposed in the threaded aperture, a threaded sleeve co-operating with the first-mentioned sleeve and the base member for locking the sleeve in a predetermined relation with the base member and an insulator that may pass through the said aperture having a threaded portion engaging the internal threads of the first-mentioned sleeve for adjustably supporting the insulator.

8. A bus-bar structure comprising a base member having an aperture therein, an insulator that may pass through the said aperture and a rotatable member cooperating with the base and the said insulator for adjustably supporting the insulator whereby longitudinal movement may be imparted to the insulator without rotation thereof.

9. A bus-bar structure comprising a base member having an aperture therein, an insulator that may pass through the said aperture, and a rotatable member having threaded engagement with the insulator and the base for imparting longitudinal movement thereto without rotation of the insulator.

10. A bus-bar structure comprising a base member having an aperture therein, an insulator that may pass through the said aperture, a rotatable member having threaded engagement with the insulator and the base for imparting longitudinal movement thereto without rotation of the insulator, and means for locking the rotatable member in a predetermined position with respect to the base.

11. A bus-bar structure comprising a base member having an aperture therein, an insulator that may pass through the said aperture, a rotatable member having threaded engagement with the insulator and the base for imparting longitudinal movement thereto without rotation of the insulator, and means for locking the rotatable member in a predetermined position with respect to the insulator.

12. A bus-bar structure comprising a base member, an insulator and a rotatable member having threaded engagement with the insulator and the base whereby the former may be adjusted longitudinally with respect to the latter without rotation of the former.

13. A bus-bar structure comprising a base member, an insulator and a rotatable member having threaded engagement with the insulator and the base whereby the former may be adjusted longitudinally with respect to the latter without relative rotative movement of the base and insulator.

In testimony whereof, I have hereunto subscribed my name this 18th day of November, 1919.

JAMES M. BROWN.
